US0D1062569S

(12) **United States Design Patent** (10) Patent No.: **US D1,062,569 S**
(45) Date of Patent: ** Feb. 18, 2025

(54) **WHEEL**

(71) Applicant: **Howmet Aerospace Inc.**, Pittsburgh, PA (US)

(72) Inventors: **Spencer Wallace**, Broadview Heights, OH (US); **Logan Klink**, Olmsted Township, OH (US); **Mateusz Kowalski**, Parma, OH (US)

(73) Assignee: **HOWMET AEROSPACE INC.**, Pittsburgh, PA (US)

(**) Term: **15 Years**

(21) Appl. No.: **29/822,062**

(22) Filed: **Jan. 5, 2022**

(51) LOC (15) Cl. **12-16**

(52) U.S. Cl.

USPC **D12/204**

(58) **Field of Classification Search**

(57) **CLAIM**

The ornamental design for a wheel, as shown and described.

DESCRIPTION

FIG. 1 is a front perspective view of a wheel, showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate portions of the wheel which form no part of the claimed design.

1 Claim, 6 Drawing Sheets
